US00D906145S

(12) **United States Design Patent** (10) Patent No.: **US D906,145 S**
(45) Date of Patent: **** Dec. 29, 2020**

(54) **HUB**

(71) Applicant: **AMAZON TECHNOLOGIES, INC.**,
Seattle, WA (US)

(72) Inventors: **Mark Siminoff**, Mountain View, CA
(US); **Peter Gerstberger**, Laguna
Niguel, CA (US); **Spiro Sacre**, Los
Angeles, CA (US); **Christopher Loew**,
Palo Alto, CA (US); **Andrew L.
Russell**, Philadelphia, PA (US); **James
Siminoff**, Pacific Palisades, CA (US)

(73) Assignee: **Amazon Technologies, Inc.**, Seattle,
WA (US)

(**) Term: **15 Years**

(21) Appl. No.: **29/705,131**

(22) Filed: **Sep. 10, 2019**

Related U.S. Application Data

(63) Continuation of application No. 29/662,786, filed on
Sep. 7, 2018, now Pat. No. Des. 865,556, which is a
continuation of application No. 29/617,865, filed on
Sep. 15, 2017, now Pat. No. Des. 830,869.

(57)

The ornamental design for a hub, as shown and described.

DESCRIPTION

FIG. 1 is a front perspective view of the hub according to the present design;

FIG. 2 is a front elevational view of the hub of FIG. 1;

FIG. 3 is a rear elevational view of the hub of FIG. 1;

FIG. 4 is a left-side elevational view of the hub of FIG. 1;

FIG. 5 is a right-side elevational view of the hub of FIG. 1;

FIG. 6 is a top plan view of the hub of FIG. 1; and,

FIG. 7 is a bottom plan view of the hub of FIG. 1.

The broken lines in the figures illustrate portions of the hub that form no part of the claimed design.

1 Claim, 4 Drawing Sheets
